Patented Aug. 26, 1919.

Inventor:
Farnum F. Dorsey

UNITED STATES PATENT OFFICE.

FARNUM F. DORSEY, OF ROCHESTER, NEW YORK, ASSIGNOR TO NORTH EAST ELECTRIC COMPANY, OF ROCHESTER, NEW YORK, A CORPORATION OF NEW YORK.

FIELD-MAGNET.

1,314,132.

Specification of Letters Patent. Patented Aug. 26, 1919.

Application filed July 31, 1918. Serial No. 247,611.

To all whom it may concern:

Be it known that I, FARNUM F. DORSEY, a citizen of the United States, residing at Rochester, N. Y., in the county of Monroe and State of New York, have invented certain new and useful Improvements in Field-Magnets; and I do hereby declare the following to be a full, clear, and exact description of the invention, such as will enable others skilled in the art to which it appertains to make and use the same.

This invention relates to a field-magnet for use in electric motors or generators, or other apparatus.

In dynamo-electric machines of the "iron-clad" type, in which the field-poles are in the form of inward projections from a ring or shell of iron, it is common to use windings, upon the polar projections, comprising form-wound coils which are placed, already wound, on the projections. To combine efficiency with economy of material, the polar projections should have comparatively slender necks and wide faces, but this form introduces difficulty in applying the coils to the projections, unless the projections are made separable, in whole or in part, from the ring or shell of the field-magnet.

The object of the present invention is to produce a magnet, of the type in question, in which the polar projections are connected integrally, without any break in the magnetic path between them, but in which the coils may be easily applied to and removed from the necks of the polar projections.

To the foregoing end the invention resides in a field-magnet having a core which is divided into sections on planes passing obliquely through the polar projections, this mode of division facilitating the application of the coils, as hereinafter explained, without introducing any break or air-gap into the magnetic circuit.

In the accompanying drawings Figure 1 is a side-elevation, partly in section, of a two-pole field-magnet embodying the present invention. Fig. 2 is a side-elevation showing the manner in which the parts of

the magnet are assembled. Fig. 3 is a side-elevation of a four-pole magnet.

In Figs. 1 and 2 the invention is shown as embodied in a bi-polar field-magnet. The core of the magnet comprises two similar sections which, together, constitute the usual circular yoke, with inwardly directed polar projections. Each section comprises a body-portion 5, at the ends of which are inward projections 6 and 7, terminating in horns 8 and 9, respectively. The parts 6 and 7 of the two sections meet on parallel planes 10, so as to form two comparatively narrow necks on which the coils 11 are mounted in the usual manner.

The planes of cleavage 10, since they pass approximately lengthwise through the polar projections, do not interrupt the continuity of the paths of the magnetic lines of force, but they permit the coils, already formed, to be placed upon the necks, in the manner shown in Fig. 2. It will be apparent that if the coils be passed over the horns 9 and seated against the parts 7, as shown, the two core-members may then be slid together, by relative movement along their meeting faces, so as to pass the horns 8 through the coils, and the completion of this movement causes the coils to swing into position to hug the parts 6 closely.

The two core-members may be supported in co-operative relation in any convenient way: In Fig. 1 they are shown as embraced by a cylindrical shell or housing 13, which may be of magnetic or non-magnetic material. If economy of material and weight be important, the outer corners of the sections may be rounded off as shown by the dotted lines 12 in Fig. 1, without any substantial sacrifice of efficiency. The sections may also be made either solid or laminated, as may be most convenient.

The invention is applicable to multi-polar field-magnets as well as to bi-polar. Fig. 3 shows a four-pole magnet, which differs from that of Fig. 1 only in that the body-portion 14 of each section extends through an arc of only 90°.

The invention claimed is:

A field-magnet comprising an annular body and inwardly directed polar projections, each projection having a neck and 5 horns at the inner end of the neck; the magnet being characterized by the fact that it is divided, on parallel planes passing

obliquely through opposite polar projections, into a plurality of sections, each section comprising a yoke or body-portion and, 10 at each end, approximately half of a polar projection.

FARNUM F. DORSEY.
